UNITED STATES PATENT OFFICE.

JOHN FLOYD BALL, OF ESTEP, WEST VIRGINIA.

WIRE-FENCE STRETCHER.

1,387,338.

Specification of Letters Patent.

Patented Aug. 9, 1921.

Application filed March 8, 1921. Serial No. 450,728.

To all whom it may concern:

Be it known that I, JOHN F. BALL, a citizen of the United States, residing at Estep, in the county of Boone and State of West Virginia, have invented certain new and useful Improvements in Wire-Fence Stretchers, of which the following is a specification.

This invention relates to certain new and useful improvements in wire fence stretchers.

10 The object of my invention is to provide a simply constructed, readily operated wire fence stretcher, by means of which a wire fence fabric can be readily stretched to the proper degree of tautness with ease, accuracy and despatch.

With these and other objects in view the present invention consists in the combination, and arrangement of parts as will be hereinafter more fully described and finally 20 pointed out in the appended claims, it being further understood that changes in the specific structure shown and described may be made within the scope of the claims, without departing from the spirit of the invention.

25 In the accompanying drawings forming a part of this specification, and in which like numerals of reference indicate similar parts in the several views:

Figure 1 shows a side elevational view of 30 a wire fence stretcher embodying my invention.

Fig. 2 is a top view of Fig. 1.

Fig. 3 is a front view.

35 Fig. 4 shows the clamping member as detached and open.

Fig. 5 is a detail of one of the adjustable spurs.

40 Fig. 6 is a section through the clamping bar, on line 6—6 of Fig. 3.

45 Referring to the drawings for a more detailed description of my invention, the numeral 1 designates the intermediate portion and 2 the two parallel stems of a U-shaped frame member made of bar metal or iron tubing. Fixed to the stems 2, 2 are the oppositely held bearings 10, 10, which hold the main driven shaft 12 having the bearing ends 11 shown in Fig. 2. Fixed near the upper end to the shaft 12 is the bevel

50 gear 13 while secured intermediate of its ends is the staple 14 from which extends the winding chain 15 to which are fixed the two stub chains 16 the ends of which are secured to the staples 45 extending from the 55 rear edge of a main clamping bar 18.

Held to the bar portion 1, is a bearing giving support to the stub driving shaft 23 to which is fixed the bevel pinion 24 in mesh with the gear 13, the shaft 23 being operated by means of the crank 28.

60 As shown in Fig. 1 the stub shaft 23 has secured to it the ratchet wheel 25, and the shaft 23 is held against longitudinal displacement by means of the members 24 and 25.

65 Pivottally held to the frame 1, is the pawl-plate 26 to which is held the pawl 27. A spring 30 presses the pawl against the wheels 25.

70 Each frame member 2, has secured to its end a bolt 3 engaged by a wing-nut 4 and slidably engaged in these ends are the sleeves 7 of the adjustable spurs 6, each spur ending in an offset point 8, a middle lengthwise extending slot 5 being provided to receive 75 the bolts 3 in the manner shown in Fig. 5.

75 In order to securely hold the fence fabric F, to the stretcher, I provide a specially constructed clamping member including the main hinge-bar or clamping bar 18 ending 80 in hinge-ears 19 and 20 adapted to hingedly receive the upper stub hinge bar 33 and the lower hinge bar 34, these bars being arranged to coat with the main bar 18 for 85 clamping wire fabric in the manner shown in Figs. 3 and 6. The upper bar 33 has the hinge-ear 3' engaging with the ears 19 while the lower bar 34 has the hinge-ear 4' engaging with the ears 30, as shown in Figs. 1 and 4.

90 The stub clamping bars 33 and 34 each have a middle lengthwise extending rib a'. These bars have overlapping ends 39 and 40 best shown in Fig. 4. The main bar 18 has a middle lengthwise extending channel b the 95 edges of which are chamfered as shown in Fig. 6, the ribs a' being of a width less than the channel b so that the fence fabric F, may be clamped in said channel in the manner shown.

100 In order to aid in holding the stretcher in position relative to a fence post, I employ the chain 50 having one end secured to the ring 51 fixed to the frame portion 1. This chain 50 has the hook 6' adapted to engage 105 with the post on the side opposite to that engaged by the spurs 6, while the chain 50 engaged the side of the post opposite to that to which the fence fabric is to be fastened, as will be understood in referring to Fig. 2 110

where the spurs 8 are shown driven into the post so that the holder will be properly held and supported.

The instrumentalities having been properly arranged, the operation of my device is as follows; the fence fabric is clamped between the members 18, 33 and 34, by means of the bolt 46 which passes through the openings *z* and *v* in the clamping members, 10 as shown in Fig. 4. The crank 28 is then turned, and turns the shaft 12 in its bearings 10. The winding of the chain 15 on the shaft 12 will stretch the fence fabric to the proper degree of tautness, whereupon the 15 fabric can be properly stapled to the fence-post. The shaft 12 is locked against retrograde movement by means of the pawl 27.

From the foregoing description taken in connection with the drawings, the construction and operation of the invention will be 20 readily understood without requiring a more extended explanation.

Various changes in the form, proportion and the minor details of construction may be 25 made without departing from the principle or sacrificing any of the advantages of the invention as claimed.

Having thus described my said invention, what I claim as new and desire to secure 30 by United States Letters Patent is:

1. In combination with a fence post, a U-shaped frame, a transverse driven shaft held to the two parallel stems of said frame, a bevel gear fixed to said shaft, a stub driving shaft held to the intermediate portion 35 of said frame, a bevel pinion on said stub shaft meshing with said gear, a crank for operating said stub shaft, a ratchet wheel

secured to said stub shaft, a pawl held to said frame in engagement with said ratchet 40 wheel, a chain fixed to said driven shaft, a clamp secured to said chain and adapted to engage a wire fence, and a brace-chain having one end fixed to said frame, the other end engaging said post, whereby said frame 45 is braced against the tension of the fence, as and in the manner set forth.

2. In a wire fence stretcher, the combination of a U-shaped frame having its parallel stems provided with spurs for engagement 50 with a fence post, journaled bearings on said parallel stems, a driven shaft journaled in said bearings and extending at right angles to said stems, a bevel gear wheel fixed on said shaft, a fence-clamp, a chain 55 connection connecting the fence-clamp to said shaft and being windable upon the latter, a bearing on the intermediate portion of the frame, a driving shaft in the last said bearing and extending axially parallel with said stems, a pinion on said driving shaft and meshing with said bevel gear wheel, said pinion being seated against the last said bearing, a ratchet wheel on said driving shaft and seated against the last said bearing 60 at the side opposite to said pinion, a pawl mounted on said frame and engaging with said ratchet wheel, a crank for turning said driving shaft, and a brace-chain having one end engaged with the intermediate portion 65 of said frame and having its other end provided with a hook for engagement with the post on which the frame is mounted when stretching the fence-wire.

In testimony whereof I affix my signature. 75

JOHN FLOYD BALL.
